UNITED STATES PATENT OFFICE.

FREDERICK C. ROBERTSHAW, OF PITTSBURGH, PENNSYLVANIA, ASSIGNOR TO
ACHESON MANUFACTURING COMPANY, A CORPORATION OF PENNSYLVANIA.

SURFACE-FLUSHING NOZZLE.

Application filed January 3, 1927. Serial No. 158,482.

My invention relates to nozzles and particularly to surface-flushing nozzles for use in combination with men's urinals and the like.

5 One object of my invention is to provide a nozzle, of the above indicated character, that shall so compensate for discrepancies sometimes existing between the nozzle-receiving opening in a toilet structure and the 10 rear wall thereof as to ensure effective adjustment of the spray.

Another object of my invention is to provide a nozzle that shall be readily adjustable to compensate for rear walls of different 15 widths.

Another object of my invention is to provide a flushing nozzle that shall be readily adapted to accurately cooperate with urinals of widely varying character.

20 A further object of my invention is to provide a nozzle device that shall be simple and durable in construction, economical to manufacture and effective in its operation.

With such objects in view, as well as other 25 advantages which may be incident to the utilization of the improvement, the invention consists in the parts and combinations thereof hereinafter set forth and claimed, with the understanding that the several necessary elements constituting the same may be varied in proportion and arrangement without departing from the nature and scope 30 of the invention.

In urinal devices for men, it has been 35 usual to provide a structure comprising a basin or bowl-like portion at or near the floor, a rear wall surface projecting from the rear of the bowl and usually slightly curved about a vertical axis, vertical side flanges 40 for the rear wall and a flushing-nozzle to distribute a thin film of water over the major portion of the rear-wall surface from near the top thereof.

Such structures are usually constructed of 45 porcelain having relatively thick walls and considerable bulk in the manufacture of which certain difficulties arise.

One of these difficulties resides in the 50 changes of dimensions which occur during the firing operation, the initial moist mass of clay mixture being subject to warping under the intense heat of the kiln.

Thus, the openings provided in the porcelain structures for the nozzles may have 55 rather widely varying positions in different

structures of the same intended form and dimensions.

This feature naturally results in considerable confusion in the placing of the nozzles and, if the latter are of usual form, 60 widely different results are obtained. That is, the sheet-like stream ejected from the nozzle may cooperate satisfactorily with the rear walls of certain of the porcelain structures, but in others may be considerably out 65 of adjustment, causing splashing or failing to provide a proper film of water on the rear-wall surface.

Another objection to the usual standard or fixed form of flushing-nozzle is its non- 70 adaptability to urinals of different widths, these widths more recently varying approximately between twelve and twenty-four inches.

It is my aim to overcome all of the above- 75 mentioned objections and to provide a device that is not only simple, rugged and compact in construction but that is economical to manufacture and has an effective degree of adjustability.

Accordingly, in practicing my invention, I provide a flushing-nozzle in which the elements are relatively adjustable to compensate for discrepancies in the relation between the opening which receives the nozzle and 80 the surface to be flushed and in which the nozzle is also adjustable to adapt the liquid stream to urinals of various widths.

In order to make the invention more 85 clearly understood, means are shown in the accompanying drawing for carrying the same into practical effect without limiting the improvements in their useful applications to the particular constructions which, for the purpose of explanation, are made 90 the subject of illustration.

Fig. 1 of the accompanying drawings is 95 a top plan view of a toilet structure in which the nozzle of my invention is omitted;

Fig. 2 is a view taken along the line II—II 100 of Fig. 1 but with the nozzle element in position,

Fig. 3 is a side elevational view of one 105 form of the nozzle element embodied in my invention.

Fig. 4 is a view taken at right angles to Fig. 3, and

Fig. 5 is a fragmentary detail view of a 110 modified form of the nozzle structure shown in Figs. 3 and 4.

Referring to Figs. 1 and 2, a toilet structure or men's urinal 1 may comprise, in general, a bottom or receptacle portion 2, a vertical rear wall portion 3, vertical side flanges 4 and an upper or top horizontally-extending flange 5.

The receptacle portion 2 embodies a drain opening 6 and a flanged forwardly-projecting portion 7 in accordance with known practice.

The vertical rear-wall portion 3 is preferably provided with a surface 9 that is curved about a vertical axis and which is adapted to receive a thin film of water from 15 a flushing-nozzle device 10.

The nozzle device 10 is adapted to be supported in a vertical opening 12 in the top horizontal flange portion 5 which may also have an inwardly curved or cut-away 20 portion 14. The nozzle may also be supported in a horizontal opening 13, indicated by broken lines, in the wall 3, near the top thereof.

In manufacture, the structure 1 is initially carefully formed of porcelain clay batch 25 in a plastic or other readily workable state, with allowance for proper shrinkage, and kiln fired. However, by reason of air pockets, uneven distribution of moisture and other causes beyond control, shrinkage or warping other than that for which allowance 30 has been made, may occur. Thus, the opening 12 which may have been initially placed to occupy the final position, represented by the full line circle in Fig. 1, may 35 shift to some other position, as represented by one of the broken line circles adjacent thereto. Similarly, the opening 13, if provided for the nozzle in the wall 3, may also, 40 shift its position.

The shifting of the opening 12 causes the trouble, above referred to, whereby non-uniform behavior of the nozzles occur in different toilet structures of the same apparent 45 form and dimensions.

To remedy the above mentioned faults and also, to provide a flushing nozzle that is widely universally adjustable and adaptable to toilet devices of different forms, the structure 10 is provided.

In the structure 10, an externally-screw-threaded tubular member 16, for disposal in the opening 12 of the flange 5, is provided with a flange 17 between which and a similar flange 19, on a tubular member 20, the flange 5 is clamped by screwing the member 20 downwardly on the member 16. The member 20 is connected to a supply pipe 22 by a union or slip joint member 23.

60 A tube or member 24, which may be integral with the member 16, or preferably screw-threadedly mounted in the lower end of the member 16, as shown, is provided with a pivot or swivel joint portion 26 for 65 cooperation with a complementary joint por-

tion 27 of a delivery or nozzle tube 28. Vertical or longitudinal adjustment of the tube 28 may be effected by turning the tube 24 in the member 16. The joint portions 26 and 27 are connected in liquid-tight or sealed 70 relation and are held or tightened in adjusted relative position by a single element, such as a screw 30.

The mouth end of the delivery tube 28 is cut off in a diagonal plane, thereby providing an oval or ellipsoidal opening 29 therein, in order that it may cooperate with a flat plane element or plate 31 over a relatively large area thereof to effect a stream of sheet-like character extending radially from the perimeters of the tube 28 and the plate 31. The forward end or edge 32 of the plate 31 is preferably rounded similar to the oval contour of the tube 28 to assist in properly forming the water film.

80 Lugs 33, projecting laterally from the tube 28, support a pin 34 on which an arm 35 is pivotally mounted. The arm 35, preferably constituting an integral part of the plate 31, is provided, adjacent to one end, with an internally screw-threaded collar portion 38 for the reception of a screw 39, the inner end of which bears against the tube 28 adjacent to the joint portion 27 thereof. By turning the screw 39, a space 40 between the tube 28 and the plate 31 may be adjusted to vary the width of the spray laterally from the center of the nozzle as viewed in Fig. 4.

85 Thus, by several or combined manipulations of the screws 30 and 39, and movement of the tube 28, almost any desired adjustment of the stream may be obtained to compensate for discrepancies in the location of the opening 12 and to adapt the nozzle to 105 urinals of different widths.

90 Also, if the nozzle be located in the horizontal opening 13 in the wall 3, by reason of the joint 26, similar adjustments may be made.

95 To prevent back splash from the space 40, the plate 31, which is of substantially L-shape in longitudinal section, is provided with an angularly disposed portion 41 having a central recess by which it partially 110 receives the tube 28.

105 In Fig. 5, in which corresponding parts are designated by corresponding reference characters, is shown a modification of my invention which, in certain applications, may be desirable or slightly more flexible in its degree of adjustment than the structure shown in Figs. 3 and 4.

110 In this form, instead of the pivot or swivel joint formed between the tubes 24 and 28 by the parts 26 and 27 and the screw 30, a substantially universal joint is provided between the tubes 24 and 28 by substituting hollow spherical parts 43 and 44 for the parts 26 and 27, respectively.

In this form also, it is only necessary to manipulate a single element or ring 45 to adjust and lock or tighten in adjusted position, the tube 28 relative to the tube 24, 5 since the ring 45 is screw-threadably mounted on the portion 43.

By my invention, discrepancies in the locations of the nozzle-receiving openings in different toilet structures of the same intended form and dimensions, are readily compensated and the nozzles may be mounted in urinals of different widths to provide effectively adjusted water films on the surfaces 9 and to prevent spilling of 15 the water beyond the flanges 4.

I claim:

1. A nozzle comprising a delivery tube and a deflector element of substantially L-shape in longitudinal section, one arm of 20 said element having a surface so related to the mouth of said tube as to spread into sheet-like form the liquid issuing from said mouth, and the other arm of said element having a central recess partially receiving 25 said tube and preventing back splash of said liquid.

2. A nozzle comprising a delivery tube including a uniformly-cylindrical portion having a diagonal-plane transverse end to 30 provide an oval mouth opening and a deflector element adjustably mounted on said tube having a plane surface over, and closely adjacent to the plane of, said mouth and an upwardly-directed portion at the rear 35 of said opening extending laterally of said tube a substantial distance.

3. A nozzle comprising a delivery tube including a uniformly-cylindrical portion having a diagonal-plane transverse end to 40 provide an oval mouth opening and a deflector element mounted on said tube having a plane surface over, and closely adjacent to the plane of, said mouth and an up-

wardly-directed portion at the rear of said opening extending laterally of said tube a 45 substantial distance and having a central recess partially receiving said tube.

4. A nozzle comprising a delivery tube and a deflector element of substantially L-shape in longitudinal section, one arm of 50 said element having a surface so related to the mouth of said tube as to spread into sheet-like form the liquid issuing from said mouth, and the other arm of said element being upwardly directed at the rear of said 55 mouth and extending laterally of said tube a substantial distance.

5. A nozzle comprising a delivery tube having a sloping mouth end and a deflector element having a surface of greater area 60 than said end and so related thereto as to spread into sheet-like form the liquid issuing therefrom and an upwardly-directed portion at the rear of said end extending laterally of said tube a substantial distance. 65

6. A nozzle comprising a delivery tube, a deflector element of substantially L-shape in longitudinal section, one arm of said element having a rounded forward edge and a surface of greater area than the mouth opening 70 of said tube so related to said opening as to spread into sheet-like form the liquid issuing from said mouth, and the other arm of said element being upwardly directed at the rear of said opening and extending laterally of said tube a substantial distance, 75 said rear arm having a central recess partially receiving said tube, and means mounted on the tube for supporting said element and adjusting the same relative to 80 said opening.

In testimony whereof, I have hereunto subscribed my name this 30th day of December, 1926.

FREDERICK C. ROBERTSHAW.
